Primary Examiner — John Windmuller(74) *Attorney, Agent, or Firm* — C. G. Mersereau; Nikolai & Mersereau, P.A.(57) **CLAIM**

I claim the ornamental design for a cable holder, as shown and described.

DESCRIPTION

FIG. 1 is a perspective view of a cable holder, showing my new design;

FIG. 2 is a front elevational view thereof, the rear elevational view being a mirror image thereof;

FIG. 3 is a left-side elevational view thereof, the right-side elevational view being a mirror image thereof;

FIG. 4 is a top plan view thereof; and,

FIG. 5 is a bottom plan view thereof.

The broken lines showing a cable, desk and additional cable holders in FIG. 1 depict environmental matter and form no part of the claimed design.
